(57) **CLAIM**

The ornamental design for a pin connector with central signal pins, as shown and described.

DESCRIPTION

FIG. 1 is a perspective view of the pin connector with central signal pins of my new design.

FIG. 2 is a top plan view of the pin connector with central signal pins shown in FIG. 1.

FIG. 3 is a bottom plan view of pin connector with central signal pins shown in FIG. 1.

FIG. 4 is a front elevational view of the pin connector with central signal pins shown in FIG. 1.

FIG. 5 is a rear elevational view of the pin connector with central signal pins shown in FIG. 1.

FIG. 6 is a right side elevational view of the pin connector with central signal pins shown in FIG. 1; and,

FIG. 7 is a left side elevational view of the pin connector with central signal pins shown in FIG. 1.

The broken lines showing throughout the drawing figures are included for the purpose of illustrating environmental structure only and form no part of the claimed design.
